UNITED STATES PATENT OFFICE.

JOÃO M. DA CAMARA COUTINHO, OF RIO DE JANEIRO, BRAZIL, ASSIGNOR TO
COMPANHIA MANUFACTORA FLUMINENSE, OF RIO DE JANEIRO, BRAZIL,
A CORPORATION.

PRINTING-MACHINE FOR ALL KINDS OF CLOTHS OR PAPER.

No. 853,159.

Specification of Letters Patent.

Patented May 7, 1907.

Application filed December 7, 1905. Serial No. 290,773.

To all whom it may concern:

Be it known that I, JOÃO MARTINS DA CAMARA COUTINHO, civil engineer, a citizen of the Republic of United States of Brazil, residing 5 at 17 Rua Theophilo Ottoni, Rio de Janeiro, Brazil, have invented certain new and useful Improvements in Printing-Machines for All Kinds of Cloths or Paper, of which the following is a specification.

10 The invention relates to a machine for printing cloth or wall paper in which the cloth or paper to be printed is presented in the form of a continuous band and by a roller on which it is previously rolled, furnished to the 15 machine, where the band goes longitudinally with a continuous motion, between a rotative cylinder and several rotative printing rollers, distributed around the rotatable cylinder and which press the band against said 20 cylinder, the impression being made on the band during this passage which after undergoing the action of the last printing roller, leaves the machine.

The object of the invention is to furnish 25 these machines, and more especially those of printing cloth, with means permitting simultaneous operation on two bands of cloth to print them, instead of operating on one band only as at present; that is, admit between the 30 cylinder and the rollers, two bands of cloth supplied by two independent rollers so that one of the bands undergoes the action of a part of the totality of the consecutive printing rollers, from the first to the last of this 35 part, while the other band is printed by the remaining printing rollers or parts of them. Each of the said bands being switched from the central cylinder immediately after undergoing the action of the last printing roller 40 which operates upon it.

To realize the invention, supports are applied to the machines preferably fixed or formed on the arms which, in these machines, bear the supports destined to receive the roll 45 of cloth to be printed; said supports being adapted to receive a second roll of cloth to be printed and supplied, as well as the first supports, with bearings for the shaft of the second roll, with suitable brake device, and if 50 necessary with a bar adapted to direct the cloth, after leaving the additional roll, to the friction or extension bars usually employed. In the main frame of the machine, prefer-

ably below the pressure cylinder, a roller is applied to switch at a convenient point from 55 this cylinder, the band of cloth which has been printed as well as the blanket which can accompany the band of cloth if necessary.

The annexed drawing represents as an example, a manner of embodying the invention 60 applied to a machine for printing cloth which can work with two rolls of cloth and supplied with four printing rollers of which, for example, the two first are intended to print 65 the band of cloth supplied by one of the rolls and the last two printing rollers for printing the cloth from the second feeding rollers.

In this drawing Figure 1 is a diagram showing, in elevation and longitudinal section, a general view of the essential parts only of the 70 said machine, and Fig. 2 is a fragmentary view of the brake applied thereto; one side A of the main frame; the central pressure cylinder B, the printing rollers 1, 2, 3 and 4, pressing the band against the cylinder B and 75 from which the bearings and other accessories have been removed; the support arm a belonging to the side frame, supplied with bearings 5 and 6 (Fig. 2) in which revolve the shafts c and d supporting respectively the 80 rolls C and D to be printed.

m is a bar suitably fixed on the arm a or sustained in position by any other means. This bar serves to lead the band of cloth c' from the roll C in the direction of the band 85 d', coming from roll D, to unite with this band and go with it by frictional engagement and over extenssions n and e, supported on the arms a and adapted to work in the usual way.

P (Fig. 2) is a usual brake device applied to the rolls C and D.

F is the usual direction roller leading the bands c' and d' and the blankets r and s to the impression cylinder. The band c' after 95 leaving the roll F is applied on to the blanket s and goes with same on the impression cylinder B until it passes the last of the printing rollers 4, at which point it is switched from the cylinder B and lead to the oven. 100 The band d' upon leaving the roller F is presented exteriorly to the band c', on cylinder B and goes with them until it passes the printing cylinder 2, in the present example, at 105 which point it is switched from the band and cylinder B by means of direction roll H

whose trunnions are journaled in suitable bearings *f* forming part of the frame or fixed therein. The band upon leaving the roller *H* is lead to the oven, guided by means of the direction rollers as *h*.

When the bands *c'* and *d'* are of different width, the smaller width is placed to go together with the blanket *s* and be therefore printed by the rolls 3 and 4 whereas the wider band, covering the first until it is switched from the cylinder *B*, that is, after being printed by rolls 1 and 2, protects the first band, which reaches further in width, from contact with the rolls 1 and 2. When however the two bands are of the same width, the interior band not being able to laterally adjust itself perfectly with the exterior band, is therefore susceptible of being soiled by the rolls 1 and 2 and requires a protection blanket *t* to avoid this inconvenience, the said blanket *t* going between the two bands. This blanket supplied to the machine by an independent roll *T* goes between rolls *C* and *D*, enters between the bands *c'* and *d'* and goes with the band *d'* until this blanket leaves the machine to be received on a roll *T'* moved by the shaft of the impression roller *B*.

In a cloth printing machine, a frame, sup-

porting arms thereon, revoluble rollers supported by said arms and having continuous bands of material, a guide bar carried by the supporting arms for the material, extensions on said supporting arms adapted to bring the continuous bands into frictional engagement with each other, an impression roller, a series of printing rollers arranged circumferentially with respect to the impression roller, said bands adapted to be fed between the series of printing rollers and impression roller so as to have one series of rollers print one of the bands on its exterior face and the remainder of the rollers to print the other band on its interior face, direction rollers for guiding the respective bands in different directions, independent brake mechanism for the respective band receiving rollers to regulate the movement thereof, and means for regulating the brake mechanism upon the respective bands.

In testimony whereof I have hereunto set my hand in presence of two subscribing witnesses.

J. M. DA CAMARA COUTINHO.
